UNITED STATES PATENT OFFICE

RICHARD THURM AND EUGENE OSCAR ENGELS, OF SAGINAW, MICHIGAN, ASSIGNORS
TO BAKER-PERKINS COMPANY, INC., OF NEW YORK, N. Y., A CORPORATION OF NEW
YORK

TUBULAR BURNER

Application filed October 15, 1925. Serial No. 62,511.

This invention relates to burners for illuminating gas, producer gas, water gas, vaporized oils and similar gaseous fuels, and particularly to the long tubular burners 5 which are used for burning mixtures of gaseous fuels and air in substantially oxygen free atmospheres as, for example, in baking ovens. When the ordinary long tubular burner supplied with a combustible mixture of air and 10 gaseous fuel is located so that the combustion at its outlets takes place in a more or less confined space in an atmosphere that is substantially free from or at least deficient in oxygen and raised to a comparatively high 15 temperature, there is liability to objectionable and sometimes dangerous back-firing and explosions.

An object of the present invention is to provide a burner so constructed as to prevent 20 such backfires and explosions and to insure a continuous and substantially uniform combustion throughout the lengths of the burners.

Reference is had to the accompanying 25 drawings showing various embodiments of the invention in which

Figure 1 shows a burner constructed in accordance with the present invention, the view being in side elevation.

Figure 2 is a vertical sectional view 30 through the burner taken approximately on the line 2—2 of Figure 1.

Figure 3 is a top plan view of one end of the burner.

Figure 4 is a longitudinal vertical sectional 35 view of the burner.

Figure 5 is a vertical sectional view taken on the line 5—5 of Figure 4.

Figure 6 is a view in elevation of one of 40 the elements of the burner.

Figure 7 is a vertical sectional view of a slightly modified form of the invention.

Figure 8 is a top plan view of the modified 45 form of the invention shown in Figure 7.

Figure 9 is a longitudinal sectional view of a still further modified form of the invention.

Figure 10 is a vertical sectional view of the 50 form of the burner shown in Figure 9 the view being taken in a plane at right angles to said Figure 9.

Figure 11 is a vertical sectional view of that form of the invention shown in Figure 9, and taken on the line 11—11 of said Figure 9.

Figure 12 is a detail bottom plan view of 55 a portion of the burner employed in the modified form of the invention shown in Figures 9 to 12 inclusive.

Figure 13 is a longitudinal sectional view 60 of a still further modified form of the invention, and

Figure 14 is a vertical sectional view taken on the line 14—14 of Figure 13.

Referring more specifically to the drawings, and particularly to Figure 1 the reference character 25 designates a burner of the type known as "tubular." In bakers' ovens, and in similar heating apparatus several of these burners are employed and in such an installation each burner is connected, by 70 means of a pipe section 26, with a gas supply main 27. Each pipe section 26 is preferably provided with a valve 29 by means of which individual operation of the burners may be controlled. The gas is supplied to the main 75 27 by a suitable mixing apparatus 28 which serves to supply to the gas the proper amount of air to insure an efficient combustible mixture.

In the present embodiment of the invention, these burners extend from the rear wall 30 through the front wall 32 of the chamber to be heated and, aiding in the support of said burners 25, there are cross members 31 which in the present instance are in the form 80 of channel irons. The front wall of the chamber is preferably provided adjacent to each burner with an observation door 33 by means of which the burner may be from time to time inspected as to its operation.

The burner 25 comprises a suitable conduit, such as a tube preferably circular in cross-section, and said tube is provided with a slot 44 extending throughout the major portion 95 of the length thereof. Mounted within the burner 25 is a second tubular member 34 which is preferably substantially semi-circular in cross-sectional form and is positioned in the burner 25 with its flat wall extending across the diameter of the burner 25 and with 100

its curved wall conforming to the curved wall of the burner 25, as is clearly shown in Figures 2 and 7.

It is this inner tube 34 which receives the gas from the main 27 and delivers the gas through the flat wall thereof to the tubular burner 25, the flat wall being formed with a plurality of perforations 41 for this purpose.

Carried by the outer end of each burner 10 is a coupling, which coupling comprises two flanged collars 39 and 40 which have threaded connection with the burner 25 and the pipe section 26 respectively. Interposed between the flanges of these collars 39 and 40 is a 15 plate 37, which, in turn, has an opening of a shape corresponding to the cross-sectional shape of the inner tube 34. This opening receives the end of the inner tube 34, which latter is flanged as at 38 for the reception of 20 securing means preferably in the form of rivets 38' which serve to secure the inner tube 34 to the plate 37. Suitable bolts 39' pass through the flanges of the flanged collars 39 and 40 and a suitable packing 40' may be 25 employed if desired.

Extending transversely of the burner 25 are bolts 42, which bolts are spaced with respect to one another, and are so positioned as to overlie the inner tube 34. One end of 30 these bolts carries a nut 43 threaded thereon, and when in position these bolts serve to retain the inner tube 34 in position within the burner 25 and to adjust the width of the slot.

Supported upon the bolts 42 and projecting 35 through the longitudinally extending slot 44 of the burner there are two parallel bars or walls 45 which ordinarily are called check bars, and in that form of the invention set forth in Figures 1 to 6, inclusive, 40 there are two of these check bars 45 arranged in spaced relation to each other.

Positioned between the check bars 45 is a 45 bar 50 which is maintained in spaced relation with respect to these check bars by means of a wire 49 wound spirally around the bar 50 in such a manner that when said bar is in place between the check bars 45 passages 52 between the wire, the bar 50 and the check bars 45 are provided which passages permit 50 of a free flow of the fuel from the burner. This assemblage, that is the check bars 45 and the bar 50 is retained in assembled relation by means of rivets or the like 51 and is retained in position within the slot 44 of the burner 25 by means of a plurality of overlying fingers 46 and by a tightening of the nuts 43 on their bolts 42 which latter causes a contraction of the slot 44 sufficient to move the sides of said slot into engagement with 55 the check bars 45 and form a tight joint therewith. At each end of the burner 25 there is a plate 47 secured to said burner by cap screws or other suitable fastening means 60 48 and this plate is shaped to conform to the exterior of the burner 25. By means of this

plate 47, escape of fuel around the check bars at the ends of the slot is prevented.

When a burner having a double flame is desired, a construction such as shown in Figures 7 and 8 is employed. The burner illustrated in these two figures is substantially the same as that illustrated in Figures 1 to 6 inclusively with the exception that in lieu of a single bar 50, there are two bars 53 and 54. These bars in this illustration are each 70 wrapped with a strand of wire which wire is wrapped spirally about the bars as in the heretofore described form of the invention. The two bars 53 and 54 are positioned within the slot 44 of the tubular member 25 of the burner, it being understood that the slot 44 in the tubular member 25 in this form of the invention is of greater width than in the previously described form of the invention and of sufficient width to accommodate the two 75 bars 53 and 54, a spacing bar 55 and the two check bars 45. The check bars 45, the two bars 53 and 54, and the spacing bar 55 are secured together in a unitary structure by suitable fastening means illustrated in the 80 present instance as rivets 56, and this entire assemblage is retained in the tubular member 25 of the burner by the curved fingers 46 and the plates 47 heretofore mentioned.

In Figures 9 to 12 inclusive is shown a still 85 further modified form of the invention in which the inner tube 34 is dispensed with, the gas entering the tubular burner 25 direct. In this form of the invention, the check bars 90 57 are spaced by a bar 60 around which the wire 49 is wrapped to provide passages 62, and these parts are secured in this relation by suitable fastening means such as rivets 64.

In order to provide a chamber between the check bars 57 and bar 60, which chamber is 95 designated by the reference numeral 61, the bar 60 is relatively narrower than the check bars 57 and has its upper edge positioned 100 flush with the upper edges of the check bars 57. The bottom wall of the chamber 61 is 105 formed by a plate 59 secured to the check bars 57 as at 58, and to permit of gas entering this chamber 61 the plate 59 is formed with a plurality of openings 63. In this form 110 of the invention the assemblage comprising 115 the check bars 57 and bar 60 are fixed together by rivets 64 and secured in position in the slot 44 of the tubular member 25 by the fingers 46 and plates 47 in the same manner as heretofore described, and for the purpose of 120 closing the ends of the chamber 61 plates 65 are provided.

In Figures 13 and 14, a still further modified form of the invention is shown in which the check bars 66 are formed with a plurality 125 of openings 67. The bar 69 around which the wire 49 is wrapped to provide fuel passages 73 is of such a width or depth that its lower edge will occupy a position above the openings 67 and will therefore not obstruct the 130

passage of fuel therethrough. This bar 69 is held in position between the bars 66 by means of rivets or other suitable fastening means designated by the reference numeral 70. A bar 71 is secured between the inner edges of the check bars 66 by suitable fastening means which in the present instance is illustrated as rivets 72 and this construction provides a chamber 68 which has communication with the interior of the tubular member 25 through the openings 67 in the bars 66.

In those forms of the invention in which the bar about which the wire 49 is wrapped is relatively narrow, the wire is so wrapped that it presents a greater number of convolutions in a given length than is the case where this bar is of greater width thus providing relatively narrow channels which are designated by the numeral 62 in Figure 9 and the numeral 73 in Figure 13.

It will be observed that in each of the embodiments above illustrated the tube 25 is one form of a conduit for gas and the like, which has an elongated opening therein, preferably 25 but not necessarily formed as a narrow slot, and that this slot is provided with side walls which in the preferred embodiment are at least in part located within the slot and are spaced apart considerably less than their 30 width, so that when there is inserted between them mechanism, in any of the various forms shown, which form gas passages at the exterior surface, each of these passages is narrow and relatively long from inside the tube 35 outward, so that the gas has to pass a distance considerably greater than that between the plates, before issuing at its burning point. The distance between the plates may be whatever seems feasible in the particular installation and with the particular kind of gas 40 and pressure existing. No specific sizes for all the various conditions are necessary here as these will depend on conditions present. But the arrangement shown results in forms 45 which experience has determined will substantially prevent all danger of back firing and at the same time will insure a burner construction which will serve to maintain in operation the gas flames in spite of the heavy 50 steam or moisture often present in baking ovens of this character.

While we have described above various embodiments of our invention, we realize that it may be embodied in widely different forms 55 other than those shown. We, therefore, do not limit ourselves to the particular constructions illustrated and described herein.

What is claimed as new is:

1. A gas burner comprising a conduit having an elongated opening therein, an elongated bar mounted in said opening, a spacing strip wound about said bar, and surfaces engaging the strip on each side of the bar to form a series of gas passages on each side of 65 said bar.

2. A gaseous burner comprising a conduit for gas and the like having a slot therein, side plates located in said slot and spaced from each other, a passage-forming means between said plates comprising a bar and a strip 70 wound about said bar thereby forming a series of gas passages on each side of said bar.

3. In a gaseous fuel burner, a chamber having an elongated slot formed therein, two elongated plates extending along said slot 75 and projecting within the burner, a third elongated plate interposed between the first two plates and a length of wire wrapped about said third plate in spiral form to maintain the same in spaced relation to the first 80 two plates so as to provide a plurality of individual fuel passages on each side of the third plate between the same and the first two plates.

4. A gaseous fuel burner comprising a tubular member having an elongated opening, two spaced elongated bars extending along said opening and projecting within the conduit, a third bar of less width mounted between said first two bars, the first two bars 90 extending beyond the third bar within the conduit, spacing means interposed between the third bar on opposite sides thereof to space the same from the first two bars, a bar 95 extending along the inner margins of the first two bars to form a chamber between the same, and means for delivering gas from the conduit into said chamber.

Signed at Saginaw, Michigan, this 9th day 100 of October, 1925.
